UNITED STATES PATENT OFFICE.

GEORGE L. HOXSIE AND ARCHIBALD PIFER, OF BLISSFIELD, MICHIGAN.

CLAY-GRINDING MACHINE.

SPECIFICATION forming part of Letters Patent No. 248,042, dated October 11, 1881.

Application filed May 4, 1881. (No model.)

To all whom it may concern:

Be it known that we, GEORGE L. HOXSIE and ARCHIBALD PIFER, of Blissfield, in the county of Lenawee and State of Michigan, have invented certain new and useful Improvements in Clay-Grinding Machines; and we do hereby declare that the following is a full, clear, and exact description of the invention, which will enable others skilled in the art to which it appertains to make and use the same, reference being had to the accompanying drawings, which form a part of this specification.

Figure 1 is a vertical sectional view. Fig. 2 is a side view. Fig. 3 is an end view. Fig. 4 is an end view, showing the slide-boxes for adjusting the crushing-rollers; and Fig. 5 is a perspective view.

Corresponding parts in the several figures are denoted by like letters of reference.

This invention relates to machines for grinding or pulverizing clay to be used in the manufacture of brick, tile, &c.; and it consists in certain improvements in the construction of the same, which will be hereinafter fully described, and particularly pointed out in the claims.

In the drawings hereto annexed, A represents the frame of the machine, which is provided at the ends with bearings for two sets of crushing-rollers, B B, C C, the shafts of which are journaled in sliding boxes D, laterally adjustable upon the ends of the frame by set-screws E, in order that the distance between the rollers of each set may be increased or diminished at will, thus enabling the machine to grind the clay to any required degree of fineness. The upper rollers, B B, are, in practice, adjusted farther apart than the lower ones, and scrapers F are located under each roller to remove any adhering clay.

The upper part of the frame is provided with bearings for two square shafts, G G, provided with spikes H, adjusted, as shown, so as to pass between each other when the shafts, which we term the "picker-shafts," revolve. A suitably-constructed hopper, I, to receive the clay fed into the machine, is located on top of the frame.

The shafts B' B' of the upper crushing-rollers are provided with gear-wheels J J, engag-

ing loose or lazy pinions K K, arranged upon the end of the frame, and serving to transmit motion between the shafts of the upper and those, C', of the lower rollers by means of pinions D', arranged upon the latter. The said pinions D' being smaller than the gear-wheels J, it follows that the lower set of crushing-rollers are rotated at greater speed than the upper ones, this being necessary in order to compensate for the greater distance between the latter.

Motion is imparted to the machine from the main drive-shaft by means of a clutch, L, engaging the shaft of one of the lazy-pinions K. By disconnecting the clutch the machine may at any time be stopped.

The picker-shafts G G are geared together by pinions M M at one of their ends. At the other end one of said shafts is provided with a pinion, N, clamped upon it by a pair of collars, O O, which are tightened by a binding-nut, P. Motion is transmitted to the picker-shaft through the pinion N by a loose pinion, Q, engaging the gear-wheel of one of the upper crushing-rollers.

In operation the clay to be ground is fed into the hopper, when the revolving pickers serve to crush the larger lumps of clay and any stones or lime, &c., which may be found therein. It then passes down through the frame between the two sets of rollers, the lower ones of which crush it to the requisite fineness.

If any stones should be fed into the machine too large or too hard to be broken by the pickers, the spikes of the latter, when striking against such stone, will catch it and hold it between them. The driving-power will then, through the herein-described arrangement of gear-wheels and pinions, loosen the pinion N between the clamping-collars O O upon the picker-shaft, thus throwing the latter out of gear without danger of breaking any part of the machine.

Having thus described our invention, we claim and desire to secure by Letters Patent of the United States—

1. In a clay-grinding machine, the combination of the picker-shafts G G, the rollers B B C C, of which the upper ones are placed farther apart than the lower ones, and suitable

operating mechanism, as herein described, for the purpose set forth.

2. The combination, with the picker-shafts G G, geared together as described, of the pinion N, clamped upon one of said shafts by collars O O and a nut, P, and mechanism for transmitting motion to the picker-shafts through said pinion N, as and for the purpose set forth.

In testimony that we claim the foregoing as our own we have hereto affixed our signatures to in presence of two witnesses.

GEORGE L. HOXSIE.
ARCHIBALD PIFER.
